UNITED STATES PATENT OFFICE.

ARCHIBALD MARTIN, OF WEST HOBOKEN, NEW JERSEY, AND LEROY FRANTZ, OF NEW ROCHELLE, NEW YORK, ASSIGNEES TO THE COLUMBUS DENTAL MANUFACTURING COMPANY, OF COLUMBUS, OHIO, A CORPORATION OF OHIO.

TOOTH-CARDING DEVICE.

Application filed June 7, 1923. Serial No. 644,014.

The present invention is directed to improvements in carding devices for artificial teeth.

The primary object of the invention is to provide an article of this character so constructed that a number of teeth may be removably mounted on a base for display purposes and convenience in handling and shipping, the construction being such that a complete set of teeth can be displayed and shipped in proper relation and removed as needed, the removal and replacement of the teeth from the base being easily and quickly accomplished without marring the working surfaces of the teeth.

A further object of the invention is to provide an article of this character so constructed that the respective teeth will be resiliently retained on the base to prevent accidental disengagement therefrom, but are capable of being easily removed and replaced.

With these and other objects in view, as will appear as the description proceeds, the invention consists in the novel features of construction, combinations of elements and arrangements of parts, and hereinafter to be fully described and pointed out in the appended claims.

In the accompanying drawing:

Figure 1 is a front elevation of the device, Figure 2 is a transverse sectional view through the same, and

Figure 3 is a horizontal sectional view.

Referring to the drawing, 1 designates a base rectangular in shape and preferably formed from wood, but it will be of course understood that any other material suitable for the purpose may be used.

The base has driven or otherwise suitably secured thereto a plurality of aligned studs 2, which are spaced equal distances apart and have their upper ends provided with substantially circular heads 3, which are disposed transversely of the base 1 and are shaped to conveniently fit the slots 4 in the artificial teeth 5, these teeth as usual having flat inner faces 6.

An elongated metallic retaining strip 7 is employed and is formed with a plurality of cut outs 8 whereby a plurality of resultant bridge pieces 9 are produced, said bridge pieces being curved transversely to the longitudinal axis of the strip. The bridge pieces

are provided with slots 10 through which the studs 2 pass, said studs being of such length that the heads 3 thereof will be disposed slightly above the plane of the respective bridge pieces. It will be observed that when the strip is engaged with the base 1 and the slots 4 of the teeth are engaged by the studs and heads that the bridge pieces, due to their curvature, exert an outward pressure upon the flat side 6 of the teeth, thereby holding the same yieldably interlocked with said studs.

The slots 4 of the teeth have one of their ends terminating near the cutting edge of the teeth, while the other ends of said slots open at the opposite ends of said teeth, and in view of this fact the teeth can be easily attached to the base by simply placing the teeth, with their flat sides upon the base and upon sliding the teeth transversely the studs will ride into the slots and compress the bridge pieces so that the latter will exercise a constant pressure upon the teeth to hold them against accidental disengagement from the studs.

It will be of course obvious that to remove the teeth it is only necessary to place the finger thereon and move the same transversely of the base.

It will be noted that the strip 7 can be readily removed from the base 1 when no teeth are in place thereon, therefore if desired new strips can be easily substituted should it be necessary.

The heads 3 of the stud are of such contour that they can pass freely into the slots 4 in a longitudinal direction, but can not disengage the same in a lateral direction.

What is claimed is:

1. A mounting for artificial teeth comprising a base, fixed tooth holders carried by said base and projecting outwardly and laterally from the front surface thereof, and a resilient metallic strip mounted on said base and having perforations formed therein to receive said holders, said strip adjacent to said holders being provided with resiliently bowed portions arranged to exercise resilient pressure upon teeth supported by said holders.

2. A display mounting for artificial teeth comprising a base, a perforated metallic strip mounted on said base, the material between the perforations provided in said

strip being outwardly bowed to provide springs, and tooth holding studs carried by said base and arranged to project through openings provided in said spring.

3. An article of the class described comprising a base, a metallic strip arranged on said base and including longitudinally extending outer edge portions united by outwardly bowed resilient connecting webs, and

head studs carried by said base and projecting through the webs for detachable engagement with artificial teeth when the posterior surface of said teeth are in engagement with said webs. 10

In testimony whereof we affix our signatures. 15
